Attorney.

UNITED STATES PATENT OFFICE.

ERICH HESE, OF DAHLEM, NEAR BERLIN, GERMANY.

SANDING DEVICE FOR POWER VEHICLES.

Application filed June 2, 1926, Serial No. 118,348, and in Germany July 8, 1925.

My invention relates to a sanding device intended for use in connection with power vehicles, and comprising besides the sand box and the sand outlet nozzle of the same, 5 a pipe extending through the entire length of the sand box from the explosion motor of the vehicle into said outlet nozzle and conducting the motor exhaust gases into the said nozzle so as to cause them to suck the sand out of the sand box and spray it upon the street or road just in front of the rear wheels, as is usually done. More especially, 10 the invention consists in the combination of the sand box nozzle and the exhaust gas pipe 15 with a shut-off device located in the sand box nozzle between the free end of said exhaust pipe and the sand box proper. The exhaust pipe is never closed by said shut-off device, and the sand cannot enter into the sand 20 outlet as long as the said device is closed. Only when the driver of the vehicle opens it by the intermediary of the means therefor provided, the exhaust gases of the motor exert a sucking action upon the sand present 25 at and, may be, partly in, the sand box nozzle and carry it with them out of this nozzle.

I am aware of the existence of sanding devices where, if the street or road is to be 30 sanded, a certain portion of the motor exhaust gases is conducted through the sand box in order to carry away a certain portion of the sand, there being therefor, a continually operating main gas exhaust pipe 35 and a secondary gas exhaust pipe co-operating with the sand box and its nozzle, and there being required, moreover, a valve and the appertaining operating members for connecting said secondary pipe with, and disconnecting it from, said main pipe, apart 40 from the means for opening and closing the sand box nozzle in the proper points of time. The chief drawback of this known sanding device resides therein that the sand 45 is not always properly dry so that the portion of the exhaust gas acting upon it cannot always carry away a sufficient amount of the sand. In contradistinction thereto there is, in my improved device, the sand 50 heated continuously by the entire amount of the hot motor exhaust gases whereby it is constantly kept dry and in proper condition for use. Besides, while moist sand is subject to freezing in winter-time, whereby the sanding device is rendered inactive and useless, 55

this can never occur with my improved device.

The invention is illustrated diagrammatically and by way of example on the accompanying drawing on which Figure 1 is 60 a longitudinal section through the improved sanding device, Figure 2 a vertical cross-section in the plane II-II of Fig. 1, drawn to an enlarged scale, Figure 3 a longitudinal section through a portion of the sand box 65 nozzle, this figure showing a modification and being drawn to a still more enlarged scale, and Figure 4 shows a section in the plane IV-IV of Fig. 3.

In the drawing *a* denotes the sand box 70 through which extends the exhaust gas tube *b*, the first or inlet portion of which is funnel-shaped and may be provided with a sound-damping covering *c* of asbestos or the like. The exhaust branch *d* of the motor 75 terminates into said funnel, as shown in Fig. 1, *e* denotes the sand box nozzle; the tube *b* extends into this nozzle and terminates therein. The annular space or the tubular passage 80 or channel between the neighbouring portions of the members *b* and *e* closed by a shut-off device which does not in the least prevent the escape of the gases from the tube *b*.

In the constructional form shown in Figs. 1 and 2, the shut-off device consists of a divided annulus *f/g*, of which the part *f* is stationary and the part *g* movable like a semi-circular slide which may be turned from the driver's seat by any suitable means, such as rods or a rod and a rope or the like, and a 85 spring or springs (not shown) may be provided for moving the part or slide *g* back into its position of rest, i. e. its closing position, after an actuation. The actuating means may be connected with the braking 90 means of the car, if desired, but the sanding device can be operated as well perfectly independently either before the braking in order to prevent the car from skidding, or simultaneously with the braking in order 95 to assist this latter.

In the modification shown in Figs. 3 and 4 the annular channel or passage between the neighbouring portions of the tube *b* and the nozzle *e* is closed by an annular member 100 *f'* having in its lowermost portion an aperture closed ordinarily by a valve *g* attached by means of a flat spring *i'* to a curved double-armed lever *i* pivoted at *h* to the annulus *f'*. When the outer arm of this lever 110

is turned in the direction of the arrow (Fig. 4), the valve *g* is withdrawn from the aperture of the member *f'* and the motor exhaust gas can suck out of said aperture a certain amount of the sand or equivalent strewing medium, carry it away with it, and throw it upon the street or road. When the driver relieves the operating hand-lever the lever *i* is drawn back into its former position, in 10 which it closes the aperture of the member *f'*, by a helical spring *j*.

I claim:

1. A standing device for power vehicles, comprising, in combination, a sand box and a sand outlet nozzle on the same, a motor exhaust gas pipe extending through the entire length of said box into said nozzle and being the continually used exhaust pipe proper of the motor of the vehicle, and a shut-off device located in the said sand box nozzle and being so designed as never to close the ori- 20 fice of said sole exhaust pipe.

2. A sanding device for power vehicles, comprising, in combination, a sand box and a sand outlet nozzle on the same, a motor exhaust gas pipe extending through the entire length of said box into said nozzle and being the continually used exhaust pipe proper of the motor of the vehicle, and a 30 shut-off device located in the passage formed by the neighbouring portions of said sand box nozzle and said sole exhaust pipe and being so designed as never to close the ori- fice of this pipe.

3. A sanding device for power vehicles, comprising, in combination, a sand box and a sand outlet nozzle on the same, a motor exhaust gas pipe extending through the entire length of said box into said nozzle and being 40 the continually used exhaust pipe proper of the motor of the vehicle, and a shut-off de-

vice located in the passage formed by the neighbouring portions of said sand box nozzle and said sole exhaust pipe and comprising an upper stationary wall and a lower mov- 45 able one adapted to be moved from the driver's seat so as to open and close an outlet passage for the sand, substantially as set forth.

4. A sanding device for power vehicles, comprising, in combination, a sand box and a sand outlet nozzle on the same, a motor exhaust gas pipe extending through the entire length of said box into said nozzle and being the continually used exhaust pipe proper of 50 the motor of the vehicle and a shut-off device located in the passage formed by the neighbouring portions of said sand box nozzle and said sole exhaust pipe and comprising a stationary wall having an aperture in its 55 lowermost portion, a valve adapted to open and close said aperture, and means for actuating said valve, substantially as set forth.

5. A sanding device comprising, a sand box, a nozzle, means for establishing com- 60 munication between the nozzle and the interior of the box, and means for conveying a heated fluid through the box to heat the same and further discharge the fluid into said nozzle to facilitate the passage of sand 65 to the nozzle and its discharge therefrom.

6. In combination with an internal combustion engine, a sanding device comprising a sand box, a tube extending the length of the box and embedded in the sand, said tube 70 having its inlet directly connected to the exhaust of the engine, and means for discharging sand in close proximity to the outlet end of said tube.

In witness whereof I have hereunto set 80 my hand.

ERICH HESE.
